DESIGN FOR A LIPSTICK HOLDER

Virgil P. Reimer, Pasadena, Calif.

Application July 31, 1946, Serial No. 132,122

Term of patent 3½ years

(Cl. D86—10)

To all whom it may concern:

Be it known that I, Virgil P. Reimer, a citizen of the United States of America, residing in the city of Pasadena, in the county of Los Angeles, State of California, have invented a new, original, and ornamental Design for a Lipstick Holder, of which the following is a specification, reference being had to the accompanying drawings, forming a part thereof.

Fig. 1 is a side perspective view of the lipstick holder, showing my new design in closed position;

Fig. 2 is a view similar to Fig. 1, showing the lipstick holder in open position;

Fig. 3 is a side view of the lipstick holder in closed position;

I claim:

The ornamental design for a lipstick holder, substantially as shown.

VIRGIL P. REIMER.
